WALL BOARD

Filed April 22, 1927

FIG. 1.

FIG. 2.

FIG. 3.

INVENTOR.

Paul Beshers

Zahorsky & Lettner

ATTYS

UNITED STATES PATENT OFFICE.

PAUL BESHERS, OF EL PASO, ILLINOIS.

WALL BOARD.

Application filed April 22, 1927. Serial No. 185,748.

This invention has reference to a wall board, such for instance, as is used in building construction, and has for its principal object to provide such a board with a body 5 of insulating material of suitable thickness, the side of which being attachable to the building frame having applied or fixed thereto a surface covering of fire proof material, and the opposite side of said insulating material having applied or fixed thereto a covering 10 of fragile material adapted to receive surface decorations and being preferably covered with a protecting covering or sheet reinforcing said fragile material and protecting the edges thereof.

The invention has for further object to provide a wall board, the base or body of which is composed of cork; the surface or side attachable to the building frame being covered or having affixed thereto a sheet of fire proof material, preferably of asbestos and its opposite side or surface having applied or affixed thereto a surfacing material, preferably of plaster, and the exposed 25 surface of said plaster having affixed or applied thereto a covering of preferably fibrous material, such as paper, which not only acts as a reinforcement for the plaster and to protect its edges against crumbling or disintegration due to handling but which is also capable of receiving surface decorations, such as paint or other ornamentation. Both the plaster and surface covering therefor being provided with openings arranged in any desired manner for the reception of securing 30 means, such as nails, which are passed through the body and fire proof material and then secured in the building frame; the heads of said nails being seated within said 35 openings and when the wall is applied to a building frame, said openings may then be filled with plaster or other suitable filler, whereby smooth upper surface of the wall board may be presented.

That the invention may be more fully understood, reference is had to the accompanying drawing forming a part of the present description and illustrating the preferred embodiment of the invention, in 40 which:—

Fig. 1 is a perspective view of my improved wall board, the reinforcing and protecting covering or sheet for the plaster being broken away;

Fig. 2 is a front view in elevation showing

my improved wall board applied to a section of building frame work, and

Fig. 3 is a cross-sectional view, as the same would appear if taken on the line 2—2, Fig. 2.

Like characters of reference denote corresponding parts throughout the figures.

Reference being had to the accompanying drawing, 1 designates a base or body of insulating material of suitable thickness, 65 preferably ground cork, and to the side of said body which is attachable to the building frame or wall 2 is applied or fixed in any suitable manner a surface covering of fire proof material 3, preferably asbestos. To the 70 opposite side or surface of the body 1 is applied or affixed in any suitable manner a covering of surfacing material 4, such as plaster or the equivalent suitable for the purpose, which is adapted to receive surface 75 decorations, such as paint or other ornamentation not shown. Due to the fragility of plaster and other like surfacing materials which may be used, I have found it desirable to provide a protecting and reinforcing covering or fibrous material 5, such as paper, see Fig. 1, which is adapted to reinforce and protect the surfacing material 4 and prevent its body and edges from crumbling and breaking due to shipping and 80 handling. It is obvious that a wall board having this construction and arrangement of parts makes the same an ideal building material for general construction purposes, as it is impervious to fire due to the surface cov- 85 ering of asbestos, which surface is attachable to the building frame or wall; an insulator against heat and cold due to the central body of cork, and surfacing material of plaster, plaster of Paris, gypsum, or the equivalent suitable for the purpose, adapted for 90 decoration, such as paint or other suitable ornamentation; a wall board of this character, as will be understood, eliminating in building construction the use and cost of 95 providing laths and plaster.

In order that a smooth exterior surface of the wall board may be presented after the same has been applied to the building frame or wall, I further provide in the construction of the same, openings or depressions 6, see Figs. 1, 2 and 3, which may be arranged in any suitable manner, however, are preferably arranged adjacent its several edges and crosswise immediately thereof. The 100 105 110

preferred arrangement of the openings 6 afford a more standard method and form of securing the wall board to the building frame or wall 2, best seen in Fig. 3, said openings 6, see Fig. 3, being formed in the surfacing material 4 and covering therefor, exposing to view the insulating body 1 which are adapted to receive and form seats for securing means, such as nails 7. The wall board having been secured to the building frame or wall 2, see Fig. 2, the openings 6 and nail heads 8, see Fig. 3, are then concealed from view by filling the openings with plaster or other suitable filler, whereby a smooth exterior surface of the wall board may be had. Cracks or openings, 9, see Fig. 2, by reason of adjacently secured wall boards are also filled and covered in the same manner, if necessary. The application of the plaster or filler to the openings 6 and cracks or openings 9 eliminates all trace of interrupted surfaces and provides a smooth exterior wall surface for decoration, such as paint or other ornamentation.

Having thus described my invention, it is obvious that various material modifications may be made in the same without departing from the spirit of my invention; hence I do not wish to be understood as limiting myself to the exact form, construction and arrangement and combination of parts herein shown and described, or uses mentioned.

What I claim is:—

1. A wall board, comprising an insulating

body of cork, a fire proof facing of asbestos 35 fixed in juxtaposition to one surface of said body and a surfacing material of plaster fixed in juxtaposition to the opposite surface of said body.

2. A wall board, comprising an insulating 40 body of cork, a fire proof facing of asbestos fixed in juxtaposition to one surface of said body, a surfacing material of plaster fixed in juxtaposition to the opposite surface of said body, and a protecting covering for said plastic surface.

3. A wall board, comprising an insulating body of cork, a fire proof facing of asbestos 45 fixed in juxtaposition to one surface of said body, a surfacing material of plaster fixed in juxtaposition to the opposite surface of said body, and a protecting covering of fibrous material for said plastic surface.

4. A wall board, comprising an insulating 50 body of cork, a fire proof facing of asbestos fixed in juxtaposition to one surface of said body, a surfacing material of plaster fixed in juxtaposition to the opposite surface of said body, and a protecting covering for said plaster surface, said surfacing material 60 and covering therefor provided with openings forming seats for the reception of securing means.

In witness whereof, I have hereunto affixed my hand and seal this 24th day of February, 1927.

PAUL BESHERS.
